PUSH-IN TYPE LAMP HOLDER**Heinz Bauer, Essen, and Heinrich Eul and
Helmut Günther, Emmerich, Germany****Application September 30, 1954, Serial No. 459,404****Claims priority, application Germany October 5, 1953****3 Claims. (Cl. 339—72)**

The invention relates to a push type lamp socket with resilient projections engaging with peripheral abutments of the lamp base, particularly with threads of the lamp base, the projections serving to keep the lamp in its pushed-in position.

In one of the well-known arrangements of this type, the resilient projections consist of peripheral ribs cooperating with corresponding peripheral grooves of the lamp base. The casing is slit axially and, when the lamp is pushed in, is extended in such a manner as to allow the peripheral ribs to snap into the grooves of the lamp base, spring rings being provided to assist the spring action of the casing.

The reliability of such sockets leaves much to be desired, apart from the fact that their manufacturing costs are relatively high.

According to our invention, the projections consist of blades pivotally arranged at the circumference of the push type lamp socket and drawn, when no lamp is pushed-in into a radial plane by an annular spring engaging projections which are provided on each of the blades. On pushing-in a lamp they are rocked by the insertion of the lamp base about their pivots whereby their free ends snap over the peripheral abutments of the lamp base.

The advantages of this arrangement are its application to the lower part of any ordinary lamp socket, its lower manufacturing costs, and the fact that it gives the lamp a reliably firm hold. In addition the seat of the lamp is resilient and movable so that welding or corrosion of the positioning elements and socket contacts is prevented when sparks form, or such effects may easily be neutralized by moving the lamps to and fro. Due to the resilient seating, this holder is advantageous particularly also in such cases where the lamp is exposed to heavy vibration such as on vehicles, in engine rooms and the like.

Located at the upper part of the inlet opening the blades cover up the major part of it thus serving as a shield against electric shock hazard, i. e. the fingers of the hand are prevented from inadvertently entering the inlet opening and from touching the contacts.

The annular spring is preferably in the form of a helical spring shaped into a ring, which engages deflected tongues punched out from the centre of the blades.

Other features of the invention are apparent from the following description of some embodiments of the invention.

In the accompanying drawing:

Fig. 1 is a vertical cross section of the upper part of a lamp socket according to our invention.

Fig. 2 is a plane view of the lamp socket shown in Fig. 1.

Fig. 3 is a plan view of a single blade of a socket according to Figs. 1 and 2 at an enlarged scale.

Fig. 4 is a side elevation of the blade according to Fig. 3.

Figs. 3a and 4a are plan and side views, respectively, corresponding to Figs. 3 and 4 of a modification of the invention.

2

Fig. 5 is a vertical cross section of a modified form of blade mounting.

Fig. 6 is a plan view partly broken away of the device according to Fig. 5.

5 Fig. 7 is a plan view of a further form of blade mounting.

Fig. 8 is a side elevation partly in section of the lamp socket with a lamp.

By means of a thread 3 (Figs. 1 and 8) the base 24 (Fig. 8) of the socket is screwed on to an upper part or shell 2 in a well-known manner. The shell has an inlet opening 4 which widens into an extension 5 at its upper part. This extension has a recessed surface 6, on which is supported a ring 7 having at its peripheral edge a number of recesses 8 (Fig. 3). At each side of the root of each recess 8 is formed a small recessed portion 9, the small recessed portions serving as bearings for the lateral projections 11 of the blades 12 which are supported on the ring 7. The blades 12 are provided with 15 downwardly directed tongues 13 punched out of the blades.

An annular helical spring 14 is provided behind the deflected tongues 13. In their inoperative position, the blades are supported by the ring 7 in a manner shown in 25 Figs. 3 and 4. The blades 12 are inserted with their narrow ends into the clearances 8 till their lateral projections 11 have reached the recessed portions 9. Thereupon their free ends are brought into a horizontal position so that they extend underneath the ring in a radial 30 plane and the annular spring 14 is placed behind the tongues.

It will be understood from the drawing that, when the lamp base 10 is introduced into the inlet opening, as shown in Fig. 8 and, by dash and dot lines, in Fig. 1, 35 the blades 12 are swung downwards and outwards against the increasing tension of the annular spring 14 and, at the same time and with considerable spring pressure, their free ends engage with the threads of the lamp base (see the position of the left blade in Fig. 1 marked by dash and dot lines). At least one of the blades will be in intimate contact with a wall part of the thread, so that the lamp cannot be withdrawn without application of an increased power of traction or without being unscrewed.

When the blades are of different lengths, it will be possible to make all blades simultaneously contact the wall 40 parts of the threads of the lamp base or cause them eventually to take up this position after a slight rotation. In their position of rest (see Figs. 1 and 2) the end points of the blades trace out a spiral. Corresponding different lengths may be given to the blades by a simple punching 50 action, when the push type lamp socket is finished.

The ring 7 is covered by a covering ring 15 made of a plastic or other suitable material, which covering ring is provided with an annular groove above the recessed portions 9, so as not to hinder the pivoting of the blades 12. The covering ring 15 is secured in position by a 55 spring ring 16.

Longitudinal ribs 17 are provided in the lower, narrower part of the inlet opening 4 to centralize the lamp base, when it is pushed in. The blades enter the clearances between the longitudinal ribs 17, when they are swung downwards by a lamp base. In order to ensure 60 that the blades are not prevented from swinging downwards by the ribs 17, the ring 7 is secured by means of a groove-and-tongue joint 18 to maintain it in a predetermined position inside the shell 2.

Referring to Figs. 3a and 4a, the blades 12, at their outer ends, are provided with a narrow transverse slot 19 adapted to be slid over a finger 20 bent downwards from the ring 7. The blades 12 can also be mounted by bending over their outer ends and embracing a wire ring or by 70 means of transversal pins fixed at their outer ends.

Referring to Figs. 5 and 6 the mounting of the radial blades 12 is effected by means of a bearing ring 21 made of plastic and, at its lower part, is provided with projections 22 equi-spaced according to the width of a blade 12.

At their roots, the projections 22 are provided with recesses 23 in which engage the projections 11 of the blades. The bearing ring does not require a cover ring because it is secured to the shell 2 of the socket by means of a spring ring 16.

In the modification according to Fig. 7 the blades 12 of different lengths together with their ring 7 consist of one single piece punched out of a thin and resilient sheet of material. The articulated joint of the blades is replaced, in this instance, by the flexibility of the blades, which allows bending down of the blades 12, when the lamp base is introduced into the holder. The annular spring 14 is also used and is engaged behind the downwardly bent tongues 13 to ensure the pressure required for the pressing of the blades against the lamp base and for the withdrawal of the blades into their position of rest, when the lamp base is withdrawn.

The lamp base may also be provided with a cylindrical circumferential face instead of with an Edison-screw thread, the face having corresponding peripheral grooves or other recesses or elevations.

The design according to the invention does not require any enlargement of the largest diameter of the usual socket body 2. As the lamp is not screwed in but simply pushed in, it is not necessary to provide the lamp socket with elements to guard it against being screwed in relation to the supporting members, which elements are generally in the form of screws with clamping rings and the provision of which considerably increases the manufacturing costs of the sockets. The invention allows the lamp to be disconnected by a slight rotation, as the thread of the lamp engages the points of the blades.

What we claim, is:

1. In a push type lamp socket of the class described, a socket body having an inlet opening, current carrying parts located therein, a lamp base to be inserted therein having peripheral abutments, at least four blades terminating in free ends and connecting ends, the latter being

mounted on the inside of the socket body, connecting means between said socket body and said connecting ends adapted to enable the free ends to be swung in an arc, a projection at the under side of each blade between its free end and its connecting end, an annular spring simultaneously engaging all said projections adapted to draw the blades towards the axis of the socket body into a radial plane of the socket body, when no lamp is inserted, and to return the free ends of the blades behind said abutments, after said blades have been swung outwards by an angle of about 90 degrees on inserting the lamp, whereby said blades serve as a protection against touching said current carrying parts and hold the lamp in its inserted position in such a manner that it cannot be drawn out of the socket body without an increased power of traction.

5 2. In a push-type lamp socket according to claim 1, said connecting means having the form of pivots consisting of lateral projections at the outer ends of the blades, a ring having spaced recesses therein which extend inwards 10 from its outer periphery and recessed portions located at the internal ends of and lateral to said recesses, said lateral projections being positioned in said recessed portions, and means for holding said lateral projections in said recessed portions.

25 3. In a push type lamp socket according to claim 1, said connecting means having the form of pivots consisting of lateral projections of the outer ends of the blades, and a bearing ring having downwardly directed projections equi-spaced according to the distance of the blades 20 from each other, said projections having outer recesses below the underside of the bearing ring, the lateral projections of said blades extending into said recesses.
